(57) **CLAIM**

The ornamental design for an actuator assembly, as shown and described.

DESCRIPTION

FIG. 1 is a front perspective view of an actuator assembly showing our new design.

FIG. 2 is a front perspective view thereof.

FIG. 3 is a rear perspective view thereof.

FIG. 4 is a front elevational view thereof.

FIG. 5 is a right side elevational view thereof.

FIG. 6 is a rear elevational view thereof.

FIG. 7 is a left side elevational view thereof.

FIG. 8 is a top plan view thereof; and,

FIG. 9 is a bottom plan view thereof.

In the drawings, the broken lines depict portions of the actuator assembly which form no part of the claim.
